DESIGN FOR AN ELECTRIC SHAVING DEVICE

Cummings Gardner, Los Angeles, Calif.

Application May 12, 1937, Serial No. 69,319

Term of patent 14 years

To all whom it may concern:

Be it known that I, Cummings Gardner, a citizen of the United States of America, residing at 1188 Mullen Avenue, Los Angeles, California, have invented a new, original, and ornamental Design for an Electric Shaving Device, of which the following is a specification, reference being had to the accompanying drawing, forming part thereof.

Fig. 1 is a view in front elevation of an electric shaving device embodying the novel design.

Fig. 2 is a view in rear elevation of the same device.

The dominant feature of the design resides in the head portion of the device.

What is claimed is:

The ornamental design for an electric shaving device, as shown and described.

CUMMINGS GARDNER.
